UNITED STATES PATENT OFFICE.

JOHN MERRY, OF NEW YORK, N. Y., ASSIGNOR TO THE BIGELOW CARPET COMPANY, OF MASSACHUSETTS.

DESIGN FOR CARPET AND BORDER.

SPECIFICATION forming part of Design No. 24,571, dated August 13, 1895.

Application filed June 5, 1895. Serial No. 551,786. Term of patent 3½ years.

To all whom it may concern:

Be it known that I, JOHN MERRY, a subject of the Queen of Great Britain, and a resident of the city of New York, in the county and State of New York, have invented a new and original Design for a Carpet and Border, of which the following is a specification.

This invention comprises two parts—namely, the design A for a carpet and the design B for a border; and I do hereby declare that the drawing accompanying this specification conveys to any one skilled in the art a clear understanding of the same, and is sufficient to enable such person to use my invention.

The design A is characterized by small floral figures enwreathed in stemwork, constituting the leading feature thereof, and the design B is characterized by large floral wreaths

connected by ornamental waving bands, constituting the leading feature thereof.

What I claim, and desire to secure by Letters Patent, is—

1. In a design for a carpet, the body A substantially as shown.
2. In a design for a carpet, the border B substantially as shown.
3. The design for a carpet, comprising the body A and the border B substantially as shown.

In testimony whereof I have signed my name to this specification in the presence of two subscribing witnesses.

JOHN MERRY.
